CIGARETTE DISPENSING DEVICE AND
ASSOCIATED MECHANISMLouis V. Aronson, Newark, N. J., assignor to Art
Metal Works, Inc., a corporation of New
Jersey

Application March 20, 1930, Serial No. 437,327

1 Claim. (Cl. 312—78)

This invention relates to a cigarette storing and/or dispensing device. One of the objects of the invention is to provide a simple compact device of this kind to supply the usual requisites for cigarette smoking. Another object is to provide in such a device an efficient cigarette dispenser. Another object is to provide a device of the kind mentioned which may be inexpensively manufactured, shall have few moving parts and which shall not be apt to get out of order. Other objects and advantages will more clearly appear from the following description taken in conjunction with the attached drawings forming part of this application.

15 The invention accordingly comprises the novel devices and combinations thereof, specific embodiments of which are described herein by way of example only and in accordance with the manner in which I now prefer to practice the invention.

20 Referring now to the drawings, Fig. 1 is a perspective view of a device embodying my invention;

Fig. 2 is a somewhat enlarged fragmentary plan view showing the top open and a number of cigarettes in place;

Fig. 3 is a sectional elevation taken on the line 3—3 of Fig. 2, the top having been closed with the cigarette lighter in place;

30 Fig. 4 is a longitudinal sectional view through the device, part of the device being broken away;

Fig. 5 is a plan view of part of the underside of the device; and

Fig. 6 is a fragmentary sectional view showing 35 the ejecting means ready to eject a cigarette.

Referring now in detail to the drawings, there is shown a substantial oval hollow base 1 preferably made of metal and of sufficient height to accommodate part of the mechanism of an 40 ejector to be described later. At one end of the base is a saucer-shaped depression 2 which serves as an ash tray. At the opposite end of the base is a hollow cylindrical casing 3 also preferably of metal provided with a hinged metal top 4 having 45 an aperture 5 through which a cylindrical lighter 6 projects, the lighter being provided with shoulders 7 resting on the edge of the aperture 5. The operating elements of the lighter may be such as described, for example, in my pending application Serial No. 358,483, filed April 27, 1929.

Inside the casing 3 is a feeding device 8 spaced from the interior of the casing for moving cigarettes in the casing. As here shown, it consists of the hollow rotatable cylindrical drum having 50 a curved upper edge and arranged concentrically

with respect to the casing 3. This drum and casing is arranged to hold cigarettes 9 between its outer wall and the inner wall of the casing 3 in an annular feedway 9a. The drum is also preferably of metal. The drum is provided with five 60 equidistantly spaced radial fins, four of which, each designated by the numeral 10, are of slightly less width than the drum 8 (as shown more clearly in Fig. 4). The fifth fin which I have designated as 11 (see Fig. 3) is of considerably greater 65 height than the drum and extends approximately the height of the interior of casing 3. The fin 11 is about equal to the width of the annular space between the casing and drum. The width of each of the fins 10 is about equal to half of the space. 70 The reason for the differences in width and height of these fins 10 and 11 is that fin 11 serves to contact with a stop 12 (see Figs. 2 and 4), which stop is approximately the height of the inside of the casing 3 and is attached to the inner wall thereof. 75 Its width at the top is slightly less than that of the annular space 9a, but at a point about one-third of its height it is narrowed so that the fins 10 may pass it when they rotate with the drum 8 as hereinafter described. This arrangement 80 allows the drum to make one complete rotation until the stops 11 and 12 meet one another. The bottom 13 of the drum 8 has a projecting ledge 14 which projects a distance equal to a little less than the width of the fins 10. This ledge aids in 85 supporting the cigarettes in the feedway 9a.

Mounted about centrally of the bottom wall of the casing 3 is a substantially vertical axle 15. A helical coil spring 16 has one end suitably attached to the upper part of this axle, the body 90 of the spring lying about the casing 17 surrounding the axle and the lower end being suitably attached to the floor 13 of the drum. The motion of the drum under the influence of this spring is as stated above, to make a complete 95 revolution from the place where the stop 11 is just in front of the stop 12, viewing the stop 12 as it is shown in Fig. 4, until stop 11 has made one complete rotation and comes to rest back of stop 12. The rotation viewed from above is a 100 clockwise rotation. The spring 16 is arranged to produce such rotation and is also arranged to be under tension when the stop 11 comes to rest back of stop 12, so that during its entire movement the drum is under tension. This means that 105 the line of cigarettes 9 in the annular space 9a are under pressure from the spring 16 which pressure urges them in a clockwise direction towards an ejector, which will be described later, and so that a cigarette is replaced by its im- 110

mediate successor upon removal of that cigarette from the casing 3. The fins 10 therebetween tend to keep the cigarettes in proper upright position and when the first of the series of four 5 cigarettes between the lower pair of fins shown in Fig. 2 comes to rest against the stop 12, this series of four cigarettes is pressed between the fin on the right-hand of the series and stop 12 in Fig. 2. This pressure aligns the cigarettes 10 properly in vertical position to be ready for successive ejection. Similarly when the next series of four cigarettes comes to the ejecting position, the first of the series contacts with stop 12 and these cigarettes are aligned between the stop and 15 the fin on the right of that series.

The cigarette resting against stop 12 in Fig. 2 is ready to be ejected. The ejector comprises a lever 18 pivoted at its center and supported by a bracket 19 depending from the lower side of the 20 upper wall of the casing 1. This lever has a forked end 20 operating with a pin 21 mounted on a plunger 22 with a button 23 operating in a collar mounted on the upper face of the casing 1. A coiled spring 24 about the pivoted shaft on 25 which the lever 18 is mounted, tends to keep the lever in position shown in Fig. 3. The opposite end of the lever from the forked end 20 is also forked as at 25 for operation with a pin 26 mounted on the engaging plunger 27 sliding 30 in a sleeve 28 mounted on the lower side of the casing 1. The plunger is a little less than half the width of the annular space 9a in diameter and is so positioned that it projects vertically into this annular space against the end of the cigarette 9 above it and forces it upwardly for a short 35 distance as here shown about one-half to three-quarters of an inch. The height of the average cigarette is about equal to the height of the casing 3 so that this throw forces the cigarette to project above the top 4 of the casing through an opening 29 from which it may be removed by 40 grasping it with the fingers and is thus dispensed. Immediately upon removal of this cigarette, the drum swings under the action of the spring 16 and 45 the next cigarette in series is advanced to ejecting position whereupon the ejector which meanwhile has been retracted by the spring 24 is ready to eject this cigarette. This action may be continued until all of the cigarettes are ejected.

50 The cigarettes may remain in the casing for several days or even longer while waiting to be used. It is desirable to keep the tobacco therein from drying out and for this purpose I have left the drum 8 open at the top and with a suitable 55 space around the axle casing and spring to receive a wick of cotton or other water-absorbent material 30 which is here shown coiled about the interior of the drum.

Upon ejecting the cigarettes I have provided 60 conveniently at hand and as part of this unit, the lighter 6 which is removable and may be lifted out of the cover and held in the hand in position for lighting the cigarette, after which it may be replaced in the aperture in the cover 4. It will 65 be noted that the dimensions and form of this lighter are such as to allow it to seat snugly in the casing without interfering with the action

of any of the parts and at the same time to utilize the available space thus maintaining the compactness of the unit.

The operation of the device which should be largely obvious from the foregoing, is briefly summarized as follows. Cigarettes 9 are placed in the annular space 9a between the casing and rotatable drum 8. Any number of cigarettes less than the total capacity of the container may be inserted. When filled to capacity in the embodiment here shown, the position of the parts is as shown in Fig. 2. Of course it will be noted that the cigarettes between the last two sets of fins are not shown in this figure. The cigarettes being in position in order to eject a cigarette the button 23 is pressed downwardly against the action of the spring 24 thereby raising the forked end 25 of the lever 18 to raise the plunger 27 against the lower end of cigarette 9 whereupon it is moved upwardly a short distance until it emerges through the hole 29 whereupon it may be grasped and withdrawn by the user. Upon release of the button 23 the plunger 28 descends under the action of spring 24 and the next cigarette in line is then moved into position over the ejector.

The operation of the humidor and lighter has been above referred to.

The device is a simple effective unit. It is inexpensive to make. It is compact and there are few parts and these are not apt to get out of order.

While I have described my invention in detail and with respect to a certain embodiment thereof, I do not desire to be limited to such details or forms, since many changes and modifications may be made and the invention may be embodied in other forms without departing from the spirit and scope of the invention in its broader aspects. Hence I desire to cover all modifications and forms coming within the language or scope of the appended claim.

What I claim as new and desire to secure by Letters Patent is:

In combination, a vertically extending casing of generally cylindrical form provided with a dispensing opening, a supporting base therefor, a substantially cylindrical carrier member mounted for rotatable movement only within said casing for carrying a plurality of cigarettes extending vertically at the periphery of said carrier member and between the same and said casing, an axle extending vertically from said base and defining the axis of rotation of said carrier member, a spring coiled around said axle for biasing said carrier member in one direction, coacting stops for limiting rotation of said carrier member under the influence of said spring, and means for dispensing cigarettes one at a time through said opening, said spring, for each dispensing operation, moving said carrier member a distance approximately equal to the diameter of a cigarette, said dispensing means comprising a guide tube extending vertically below said dispensing opening, a rod reciprocatory in said guide tube, a lever pivoted to said rod, and a reciprocatory member for operating said lever.

LOUIS V. ARONSON.
